SPRING LATCH

Leonard Ruegg, Inglewood, Calif.

Application March 22, 1937, Serial No. 132,231

2 Claims. (Cl. 292—332)

This invention has to do with improvements in spring latches and consists of the hereinafter described novel combinations and arrangements of parts together with parts which, in themselves, are novel, by virtue of which I aim to provide a spring latch which is economical of manufacture, durable, and in which the latch lever is yieldably but positively held in the desired position by novel means.

Other objects and corresponding accomplishments will appear obvious to those skilled in the art from the following description wherein, by way of example, I describe a preferred embodiment of the invention. In this connection, however, I wish it understood that while I resort in this description to various details of combinations, arrangements and parts, my invention, in its broader aspects, is not to be restricted to such details. On the contrary, it is to be restricted only as appears from the appended claims.

For purposes of the following description, I shall make reference to the annexed drawing, in which:

Fig. 1 is a back view of my latch, in elevation, with the parts in latching position;

Fig. 2 is a view similar to Fig. 1 except that the parts are in open or unlatched position;

Fig. 3 is a side elevation of my latch;

Fig. 4 is an elevation showing the latch lever in engagement with the keeper;

Fig. 5 is a section on line 5—5 of Fig. 1; and

Fig. 6 is a front elevation of my latch and keeper.

My latch has a metal housing 10 having flanges 11 through which holes 12 are provided for securing the device to the face of a door. Within body 10 latch lever 15 is pivotally secured to post 18 by screw 16, a washer 17 being provided between the screw-head and the top of post 18, the latch lever being rotatable about post 18. Lever 15 is bifurcated at its inner end to present spaced fingers 20, 21, and at what may be termed the under side of lever 15 there is a lug 24 which presents a curved face.

Body 10 has at one of its sides a vertical slot 25 between body portions 26 and 27, which latter portions serve as stops for the outwardly projecting portion 15a of the latch lever to limit its vertical movement. Thus lever portion 15a rests against stop 26 when the latch is open (Fig. 2) and against stop 27 when in latching position (Fig. 1). At its outer end the latch lever has a portion 15b of reduced diameter, around which is provided a roller 30 for engage-

ment with the latch keeper, the roller being held against longitudinal escape from the lever by a washer 31 held in place by heading the end of the latch lever as shown at 32.

For yieldably holding the latch lever in either its open or closed position, I provide a leaf spring 40, which rests as one end on body lug 41 and at its other end it rests against and has a portion 42 projecting downwardly into a coil spring 44 vertically mounted in the casing and socketed between body lug 46 and one side of the body 10. Spring 40 is undulated so as to present substantially at its medial portion a raised portion 47 with relatively lower portions 48 and 49 on each side thereof. The lug 24 has a curved face which slides over the raised spring portion 47 when the latch lever is moved between its open and closed positions, and since coil spring 44 at all times additionally urges leaf spring 40 against lug 24, the latch lever is positively but yieldably held in either its open or closed position.

To manually move the latch lever about post 18, which acts as a fulcrum for the lever, I provide a handle 50 pivotally mounted on the exterior of the body between a pair of lugs 51 by a pin 52 extending through the lugs and an opening through the handle. This handle member has a finger 54 projecting through body slot 55 into the body between latch-member fingers 20, 21. Thus as handle 50 is moved about its pivot pin 52, finger 54 acts to swing the latch lever to open or closed position.

An overhanging portion 60 of handle 50 provides a recess 61 through which a lock may be inserted for locking purposes.

The operation of my device is as follows: To move the parts from the latched position of Fig. 1 to the open position of Fig. 2, the handle member 50 in Fig. 3 is moved to the right, which causes finger 54 to move latch member 21 downwardly, which in turn raises the outer end of the latch lever until it abuts stop 26 and removes it from engagement with the latch keeper 35, during which movement lug 24 rides over hump 47 of leaf spring 40. Also during this movement, the roller 30 rolls over the upwardly and outwardly tapering surface 36 of the keeper to urge the door, to which body 10 is secured, outwardly. To again latch the door, it is only necessary to push the door closed, by virtue of which pressure the roller 30 rotates in the reverse direction against keeper face 36, which moves the outer end of the latch lever 15 downwardly until lug 24 is moved slightly over the 55

center of hump 47 of spring 40, after which the pressure of spring 40 and coil spring 44 completes the closing action, automatically swinging the latch lever until its portion 15a abuts stop 27.

From the foregoing it will be observed that in order to move latch lever 15 from either its open or closed position, enough pressure must be exerted to move lug 24 over hump 47 of spring 40, which precludes any accidental opening or closing action. Furthermore my device is easy to assemble or repair inasmuch as the latch lever and latch handle are the only parts secured to the casing.

15 I claim:

1. In a latch device having a body, a latch bolt, a pivot member connecting said bolt between its ends to the body, a bolt actuating member operatively associated with one end of the bolt, and means for yieldably holding the

bolt in a predetermined position, including: a lug on the side of the bolt substantially opposite said pivot member, a leaf spring bearing against the lug and a coil spring bearing against one end of the leaf spring to urge it against the lug.

2. In a latch device having a body, a latch bolt, a pivot member connecting said bolt between its ends to the body, said pivot member extending through a side portion of the bolt, a bolt actuating member operatively associated with one end of the bolt to move the bolt about the pivot member, and means for yieldably holding the bolt in predetermined position, including: a lug on the side of the bolt substantially opposite the pivot member, a leaf spring rockably resting at one end against the body and a coil spring urging the other end of the leaf spring against said lug.

LEONARD RUEGG. 20
